MOTORCYCLE RACK

Robert H. Girvin III, 170 Locust St.,
Holliston, Mass. 01746

Filed Jan. 29, 1973, Ser. No. 327,799

Term of patent 14 years

Int. Cl. D12—11
U.S. Cl. D12—158

The Figure is a perspective view of a motorcycle rack showing my new design, it being understood that the broken lines showing part of the rear of the motorcycle are for illustrative purposes only.

The undisclosed side of the motorcycle rack is substantially a mirror image of the side shown.

I claim:

The ornamental design for a motorcycle rack, as shown and described.
